UNITED STATES PATENT OFFICE.

SILAS B. WINN, OF SALEM, MASSACHUSETTS.

DESIGN FOR A BOTTLE.

SPECIFICATION forming part of Design No. 13,323, dated September 26, 1882.

Application filed August 7, 1882. Term of patent 7 years.

To all whom it may concern:

Be it known that I, SILAS B. WINN, of Salem, in the county of Essex and State of Massachusetts, have invented and produced a new and original Design for Bottles, of which the following is a full, clear, and exact description.

Reference is to be had to the accompanying drawing, forming part of this specification, in which the figure represents a longitudinal sectional view of my newly-designed bottle.

Heretofore bottles for holding aerated and other liquids have been made to present, when viewed in elevation, a cylindrical configuration for their bodies and full convex configuration on the exterior of their bottoms.

The feature of my design consists in a cylindrical contour for the lower portion of the body, terminating in a rounded-off or partially-convex configuration for the bottom of the bottle at its junction with the body, and concave contour for the under side of the bottom, extending from and meeting the rounded-off or partially-convex portion of the bottom.

A is the exterior of the body of the bottle, 25 which is circular or cylindrical in its general contour. The bottom of the bottle is rounded off or of partially-convex configuration at B, where it meets the lower end of the body, which makes the bottle appear to present in 30 part a cylindrical body with externally-convex bottom, but which partially-convex configuration terminates below in an externally-concave contour, C, for the under side of the bottom.

Having thus described my invention, I claim 35 as new and desire to secure by Letters Patent—

The design for a bottle herein shown and described, the same consisting of the rounded-off or partially-convex portion B of the bottom where it joins the cylindrical exterior A 40 of the body, and the under side, C, of the bottom having a concave configuration on its exterior.

SILAS B. WINN.
